COATING MACHINE FOR PRINTERS' ROLLERS

Carl G. Bingham, Highland Park, Paul Fernekes, Arlington Heights, and William Wanner, Wilmette, Ill., assignors to Sam'l Bingham's Son Manufacturing Company, Chicago, Ill., a corporation of Illinois

Application May 2, 1938, Serial No. 205,502

12 Claims. (CL 91—43)

This invention relates to improvements in coating machines for printers' rollers.

One object of the invention is to provide a coating machine of the type mentioned by means of which a single roller may be coated or a plurality of such rollers will be coated under the same conditions as to temperature and viscosity of the composition and other factors affecting uniformity of the finished coats.

Another object of the invention is to provide improved means for rotating a single roller or a plurality of rollers, as well as improved mechanism for feeding the pan or composition applying means uniformly and without chatter or vibration during the coating operations to avoid formation of ripples or other imperfections in the finished product.

Still further objects of the invention are to provide readily adjustable means for accommodating rollers of different diameter, means for varying the rate of rotation of the rollers, mechanism for automatically interrupting the feeding movement of the composition applying means at the completion of a coating operation, improved roller supporting and driving mechanism, and other objects and advantages which will be apparent from a consideration of the following specification and accompanying drawings wherein:

Fig. 1 is a perspective view of an improved machine embodying the present improvements;

Fig. 2 is an enlarged broken perspective of a carriage for the composition applicator and of associated structures;

Fig. 3 is a sectional view taken on line 3—3 of Fig. 2 illustrating details of an adjustable roll-supporting means;

Fig. 4 is a section on lines 4—4 of Fig. 2, showing details of the carriage, particularly means for effecting driving engagement of the same with and disengagement from operating means therefor;

Fig. 5 is a section taken on line 5—5 of Fig. 3 of a vertically adjustable applicator supporting means;

Fig. 6 is a perspective view of the driving mechanism;

Fig. 7 is a sectional view taken on line 7—7 of Fig. 6 illustrating means for interrupting the movement of the carriage automatically at the end of a coating operation;

Fig. 8 is a sectional view on line 8—8 of Fig. 6 of a driven roll-supporting spindle;

Fig. 9 is a detached sectional view of a supplementary spindle for use with rolls provided with relatively short projecting core or shaft ends;

Fig. 10 is a broken sectional view of the composition heating tank;

Fig. 11 is a vertical longitudinal section through the applicator illustrated in Fig. 2 showing details thereof;

Fig. 12 is a section taken transversely of the machine and illustrating the dual-roll coating applicator shown in Fig. 1;

Fig. 13 is a broken elevation of the dual roller supporting bracket shown in Fig. 1;

Fig. 14 is a section taken on line 14—14 of Fig. 11;

Fig. 15 is a broken sectional view taken on line 15—15 of Fig. 12; and

Fig. 16 is a perspective view of a detached gate for controlling the flow of hot coating composition through an applicator outlet.

As shown in Fig. 1 of the drawings, the improvements may be embodied in a roller coating machine comprising an inclined guide indicated generally by the numeral 10, a housing 11 on which the lower end of the guide may be attached, a hollow pillar or post 12 which supports the forward end of the guide and a bed 13 upon which the above mentioned members are mounted. On the guide 10 an adjustable roller supporting bracket 14 is mounted for rotatably supporting the upper ends of a roller or rollers to be coated, while the lower ends of such roller or rollers are mounted in driven spindles 15 and 16 journaled in an inclined wall 11a of the casing 11 and rotated by driving mechanism within the casing. The mechanism in the casing, to be described more in detail hereinafter, operates a pump 17 which circulates hot composition material from a tank 18 upwardly through pipe 19, through a flexible hose 20 for discharge into a composition applicator member or pan indicated generally by the numeral 21, which pan is movable by a carriage 22 supported by and movable longitudinally of the guide 10. The pan 21 may be of a type for coating a single roller, as shown in Fig. 2 of the drawings, or it may be designed for coating more than one roller, as shown in Figs. 1 and 12.

The guide 10 may comprise a conventional I-beam, as shown in Fig. 12, on the upper flange of which a smooth and trued stationary guiding plate or track 10a preferably is secured.

The carriage 22, in the form illustrated, comprises a vertical plate 22a and upper and lower horizontal flanges or plates 22b and 22c, the former being arranged to slide upon the guide plate 10a and the latter being disposed beneath the lower flange of the guide 10. Mounted on the plate 22b of the carriage for transverse ad-

justment with reference thereto is a plate 23 which is slotted as at 23a for accommodating a threaded clamping member 24 whereby the plate and pan can be adjusted transversely of the 5 guide 10 into proper position with respect to a roller or rollers supported by the bracket 14 and the spindles 15 or 15 and 16. Transverse guide strips 22d guide the plate 23 during lateral adjustment thereof. A pan supporting bracket 26 10 is secured to the plate 23 as by threaded studs 27. Since it is desirable that a pan used for coating rollers simultaneously be so supported as to cause a cross-current of the composition, for reasons hereinafter explained, the member 26 15 may be secured to plate 23 in such wise as to provide for a slight cocking or tilting thereof and of a pan carried thereby. For example, a threaded stud 28 may be provided in member 26 whereby the latter can be tilted slightly, the openings in plate 23 through which studs 27 pass being sufficiently large to accommodate such movement. This arrangement enables the bracket to be adjusted readily for effecting the disposition of a wall 26a of the bracket in a vertical plane 20 or in a plane inclined to the vertical. Secured to the wall 26a of the bracket 26 is a stationary portion 29 of an adjusting mechanism by means of which a pan or coating applicator may be adjusted vertically. The member 29 carries an 25 adjusting screw 30 which passes through a threaded recess 31 in a clamping member 32 which is adapted to be clamped around a tubular neck or stem 21a of the pan 21 to which the hose 20 is attached. The pan may be detachably secured to the stem 21a by a set screw 21b, as shown in Fig. 15. Adjustment of the screw 30 in one direction or the other will raise or lower the pan 21, the member 32 being slidably secured to the member 29 by a dovetail rib 29a, 30 as shown in Figs. 2 and 5.

The carriage 22 has also mounted on its upper flange a hand operable lever 33 which is pivoted at 33a to a pair of ears 33b. The lever 33, as shown in Fig. 4, is of the bell crank type and has a laterally extending arm 33c, the free end of which is in engagement with a releasable latch operating member 34 as by extending into a slot 34a of said member. The member 34 can be vertically reciprocated by operation of the 45 lever 33, as will be seen. A locking dog or tooth 35 is carried by the member 34 beneath the top plate 22b of the carriage and may be moved into locking engagement with teeth of a gear 36 carried by a short shaft 37 which is journaled in a member 33 which in turn is secured to the plate 22b of the carriage. The gear 36 is rotatable within a recess 38a formed in the member 38 and a chain sprocket 39 is mounted on the shaft 37 in another recess 38b in the member 38, the 50 shaft 37 being journaled in the wall intermediate the two recesses. It will be seen that when the member 34 is lowered, the locking tooth or dog 35 will be moved to the dotted line position shown in Fig. 4 in interlocking engagement with the teeth of the gear 36 and prevent rotation of the shaft 37 and sprocket 39.

Secured to the guide 10, adjacent the upper end thereof, is a sprocket 40 around which passes an endless chain 41. The chain is driven by 55 means hereinafter referred to, located in the casing 11. The upper run 41a of the chain is supported in a position parallel with the direction of movement of the carriage 22 and passes through a recess 38b of the member 38 into engagement with the sprocket 39, while the lower

run 41b of the chain is disposed below the member 38. When the locking tooth or dog 35 is in the upper position shown by full lines in Fig. 4, the upper run 41a of the chain may rotate the sprocket 39, the shaft 37, and the pinion or gear 36 without effecting longitudinal movement of the carriage, as will be seen. Should the lever 33 be moved clockwise from the position shown in Fig. 4 to lower the latch operating member 34 and move the locking member 35 into engagement with the gear 36 to lock the same against rotation, movement of the upper run 41 of the chain, which, as stated, engages the teeth of the sprocket 39, will move the carriage longitudinally of the guide 10, as from the initial 15 starting position adjacent the upper end of a roller to be coated to the lower end thereof. When the lower position has been reached, the lever 33 may be swung counterclockwise manually, as viewed in Fig. 4, to release the driving 20 engagement of the drive chain with the carriage and thus halt further movement of the carriage, notwithstanding that the chain continues to operate. To preclude damaging the machine should an operator neglect to release the carriage at the end of the coating operation, adjacent the lower end of the guide 10, as shown in Fig. 7, there is provided a member 42 provided with an inclined surface 43 disposed in the path of travel of the member 34 whereby as the carriage reaches the dotted line position shown in Fig. 7, the surface 43 will have engaged the lower end of the member 34 and shifted the same upwardly, thereby releasing the dog 35 from the gear 36 and halting further downward movement of the carriage. This feature constitutes a safety provision should the operator neglect to shift the lever 33 as the carriage completes its downward stroke.

The roller supporting bracket 14 is provided with a top plate 14a which extends transversely of the wear plate 10a of the guide and is provided at the rear end thereof with a threaded clamp lever 44 by means of which the bracket may be firmly secured to the guide 10 in any 45 longitudinally adjusted position. A threaded adjusting screw 45 is provided for raising or lowering an arm 46 of the member 14 which carries one or more pairs of anti-friction rolls 47, each pair of which is arranged to support the 50 upper end of a shaft or core of a printer's roller to be coated. The pair of rolls 47 shown in Figs. 1 and 2 is supported by a bracket arm 46a and is arranged to support a printer's roller A in alignment with the driving spindle 15. As shown 55 in Figs. 1 and 13, the arm is provided with a second pair of anti-friction rolls 47a which may support a second printer's roller B in alignment with the driving spindle 16. Where two rollers are to be coated simultaneously, the outer roller 60 B, while disposed parallel with the roller A, is located with its axis at a slightly lower elevation than the axis of the roller A for the purpose above referred to and to be described hereinafter. The spindle 16, therefore, is located in a 65 position slightly lower than spindle 15, while the rolls 47a are located slightly lower than the rolls 47.

The driving mechanism within the casing 11 preferably comprises an electric motor 48 which, 70 by means of speed reducing mechanism 49, drives a gear 50 which in turn drives a gear 51 mounted on a shaft 52. Also mounted on a shaft 52 is a cluster of gears indicated by the numerals 53 which, in conjunction with a second cluster of 75

gears 54, constitute a transmission mechanism. The gear cluster 54 is shiftable along a shaft 55 on which the gears are mounted for effecting different rates of rotation of a shaft 55a on which 5 is mounted a sprocket 56. The shaft 55a is driven through a universal connection 55b due to the fact that the shaft 55a is arranged parallel with the inclined spindles 15 and 16. The shaft 55a may be journaled at the forward end 10 in a bearing (not shown) supported by a wall of the casing. Around the sprocket 56 and sprockets 57 and 58, the latter two of which are mounted respectively on inclined shafts 59 and 60, is a chain 61 which thus drives the roller 15 rotating spindles or socket members 15 and 16. The shafts 59 and 60 are carried by suitable journals or bearings 59a and 60a, respectively, which may be mounted on the rear of the inclined wall 11a of the casing. An idler sprocket 20 63 is shown in engagement with the chain 60 for keeping the same under proper tension. Where the machine is designed for coating a single roller, the spindle 16 is omitted, in which case the drive chain 60 will pass around only the 25 sprockets 56 and 57 for operating the spindle 15.

For varying the rate of rotation of the spindle 15 or spindles 15 and 16, where both are employed, and consequently of the roller or rollers to be coated, a gear shift mechanism of conventional form and indicated by the numeral 63 30 may be provided and is operable by a lever 65 located on the outer wall of the casing 11 as shown in Fig. 1. A clutch mechanism, also of conventional form and indicated by the numeral 35 66, may likewise be provided and is operable from the outside of the casing by a lever 67, also shown in Fig. 1. The shaft 55 is provided with a sprocket 68 which drives a chain 69 which passes around a drive sprocket 70 of a second 40 speed reducing member 71 provided with a driven sprocket 72 over which the feed chain 41 passes and by means of which it is driven. By the drive mechanism shown, varying the rate of rotation of the spindles by the gear shift mechanism 45 varies in a definite ratio the movement of the carriage.

The upper and lower runs 41a and 41b of the chain 41 pass through openings on the inclined wall 11a of the casing and over idler sprockets 50 73 and 74, respectively, which are shown as being mounted in a suitable bracket 75 attached to the inner surface of the wall 11a of the casing. The spindles 15 and 16 preferably are of the form shown in Fig. 8, where the spindle 15 is 55 shown in longitudinal section. As therein illustrated, the spindle is shown as provided with a conical recess 15a into which may be inserted the lower end of a roller shaft or core. Supplementary spindles 15' of the type shown in Fig. 9 60 may be used in coating rollers having relatively short projecting core ends. By screwing a supplementary spindle 15' into one of the others, the lower end of the body of the roller supported thereby will be spaced sufficiently from the casing 11 so that the coating operation will be completed by the applicator before interruption of the downward movement thereof by member 42. The conical surface 15a and also the corresponding conical socket or spindle 16 center the rollers 65 with respect to the spindles and accommodate roller shafts of different diameter while the rolls 47 and 47a support the upper ends of the roller shafts or cores in parallelism with reference to the direction of travel of the pan or coating applicator 21 as the latter is moved downwardly 70 75

by the carriage 22, it being understood that by adjusting the screw 45 of the member 14, the rollers 47 and 47a can be raised or lowered as may be necessary in effecting such parallel disposition of the roller shafts or cores. 5

In coating one or two rollers with the present improvements, the rollers are placed in their respective positions shown in Fig. 1 after the carriage 22 has been moved manually to an upper position adjacent the journaling bracket 14. Hot 10 coating composition in the tank 18 is drawn through a pipe 18a by the pump 17 which is driven by a shaft 17a, and forced upwardly through the pipe 19, through the hose 20 and hollow stem 21a of a pan 21. The composition 15 flows into the applicator and overflows therefrom into a trough 76 from which it is directed back into the tank 18. The composition supplied to the applicator, as is well known, is in excess of that required for merely coating the rollers and 20 surplus composition overflows the rear walls of the pan and thence into the trough 76.

When the temperature of the composition flowing through the pipe 19 and into the pan 21 is proper for the best results, as indicated by 25 a thermometer 11, for example, the clutch lever 76 is shifted, whereupon the spindles 15 and 16 are rotated at a rate dependent upon the setting of the transmission lever 65. The rate of rotation is, of course, adjusted in accordance with 30 the diameter of the rollers being coated so as to avoid splattering the composition from one roller to another or wasting the same due to excessive peripheral speed of the rollers, or as other conditions require. By shifting the locking lever 35 33 clockwise, as viewed in Fig. 4, the carriage 22 is locked to the upper run 41a of the chain 41 which is driven by the sprocket 12. The carriage thus moves downwardly from a position at the upper ends of the rollers A and B throughout 40 the length of their coatable surfaces. At the completion of the coating operation, the lever 33 is thrown manually to drive-releasing position or it is moved to that position automatically by the engagement of the member 34 with the inclined surface 43 of the automatic releasing device 42. 45

In order to avoid irregular or chattering movement of the carriage 42 during the coating stroke thereof, means are provided for preventing play 50 between the interengaging teeth of the sprocket 39 with the links of the chain 41. In the form of the invention shown, a chain 78 has one end attached to the carriage 22 and extends upwardly along the upper surface of the guide 55 member through a slot 79 in the bracket 14, around an idler roller 80 at the upper end of the supporting pillar 12, and is attached at the opposite end as at 81 to the pillar. A counterweight 82 is supported by the chain within the 60 pillar 12, as shown in Fig. 1, and constantly maintains sufficient tension on the chain 78 to prevent play between the coating links of the chain 41 and the teeth of the sprocket 39. The arrangement described assures the uniform non- 65 chattering movement of the carriage during its coat-applying stroke, thereby avoiding the formation of ripples or irregularities in the applied coating of the roller or rollers.

The tank 18 may be of any suitable construction, but the preferred form is illustrated in Fig. 10. The tank as shown is provided with an inclined bottom 18a beneath which is disposed one or more heating elements, such as heating elements 83, which heat water or oil 70 75

in the jacket 84 whereby the composition in the tank proper is maintained at a proper temperature. A screen or like foraminous member 85 is provided below the level of the composition in the tank and through which passes the composition returned by the trough 76. The screen retains bubbles formed in the returned liquid until they break since if permitted to be carried around to the applicator 21, they would be the cause of slight imperfections in the finished coating. The outlet pipe 18a is provided with an interiorly threaded intake 18b, as shown in Fig. 10, through which the composition flows to the pump 17. In order to flush out the composition material which may remain in the pipeline and the pump, a tube or standpipe 86 is provided which may be screwed into the threaded opening of the member 18b. Hot water or other solvent may be then poured into the upper end of the tube 86 which extends above the level of the composition in the tank, and by the operation of the driving mechanism, the pump will force the water up through the pipe 19, tube 20, and flush out the coating composition that may have remained therein.

The specific forms of applicator 21 shown in Figs. 1, 2, 11 and 12 preferably are formed as castings or they may be fabricated of sheet metal. The single roller coating type shown in Figs. 2 and 11 differs from the multiple roller coating type shown in Figs. 1 and 12 merely in the size or length thereof and in that the latter is provided with two semi-circular recesses in the front and rear walls of the two sections thereof which accommodate the printers' rollers. The forward wall of each type, whether the single or multiple roller coating type, is provided at the margins of the semi-circular recess or recesses therein with rubber dams 87 which embrace the respective rollers closely to prevent downward flow of the composition material along the roller in advance of the applicator. Since the usual coating composition congeals quickly, any downward flow of the material along the roller will form irregularities in the finished coating.

As stated above, the applicator is flooded with the coating material during the coating operation, the surplus overflowing at the rear edge for reasons well known in the art. The applicator shown herein is provided, however, with an overflow port 88 communicating with a passage 89 which returns the overflowing material to the trough 76. The object of the overflow 88 is to create a cross-current of hot liquid from the intake side thereof to said outlet so as to prevent retention of a localized body of composition material in the applicator for such length of time as will enable it to congeal. With applicators of the former type not having such overflow to induce a cross-current of hot material throughout the length of the applicator, it has been found that not infrequently, the material at the side of the pan remote from the intake, that is, the lefthand side as viewed in Fig. 12, does not circulate but remains in the pan and becomes partially congealed during the coating operation, and portions of such congealed composition material when liberated are carried to the roller and form lumps or imperfections in the finished coat. By means of the constant overflow of the fluid composition during the coating operation, this cause of imperfect rollers has been obviated since the material is free to flow lengthwise of the pan from the intake to the overflow side thereof, and thus congelation

or partial congelation of the liquid in the applicator at the side remote from the intake is avoided. To induce the free flow of the liquid through the overflow passage 89, the passage preferably communicates, as by an extension 90, with the atmosphere, the upper end of which is at a level above the normal level of the liquid in the pan during the coating operation.

For the purpose of facilitating the flow of composition material from the intake end to the opposite end of the applicator and thereby avoid undesirable temperature variations in the composition within the pan and consequent variations in the viscosity thereof and to enable the regulation of the level of the composition in the coating sections of the applicator, the latter preferably is inclined from the intake to the opposite end thereof, as illustrated in Figs. 1 and 12. For this reason, the roller B, that is, the roller more remote from the intake end of the applicator, is located at a slightly lower level than roller A. Consequently, spindle 16 is at a lower elevation than spindle 15, and rolls 47a are correspondingly lower than rolls 47.

A sheet metal gate 91, shown in perspective in Fig. 16, and having an arm 91a which engages a rear wall of the applicator, may be utilized for varying the area of the overflow opening as may be desirable. Such gates 91 are shown in position in Figs. 11, 12 and 14. In addition to the use of a gate at the overflow opening, where a dual or multiple applicator is being employed, a second gate 92 is employed between the rollers as shown in Fig. 12. By using a gate 91 at the overflow opening of either the single or the multiple roller applicator and a second gate 92 between the rollers in an applicator of the latter type as shown in Fig. 12, the level of the composition in the applicators can be so regulated as to obtain the most satisfactory results under varying operating conditions. Since variation in the level of the roller-contacting composition in the applicator tends to vary the smoothness of the applied coating, it is desirable to maintain the level in the coating sections of the applicator at the same height with respect to the respective rollers being coated to procure uniform results. Hence, in coating a plurality of rollers simultaneously, suitable means such as a gate or gates 92 are employed to so impede the flow of composition material from an upper to a lower coating section of the inclined applicator that the level of the composition in the sections will be uniform with reference to the respective rollers. By means of the gates, the level of the composition in the applicator can therefore be varied within desirable limits for controlling the smoothness of the applied coating under different rates of rotation of the spindles and velocity of movement of the carriage, and under temperature or other conditions affecting the viscosity of the coating composition.

The gates 91 and 92 preferably are so shaped at their lower ends as to be incapable of obstructing completely the flow of composition through the outlet ports or from one roller coating section of the multiple roller coating applicator to a lower section.

With the apparatus shown and described, a single roller may be coated, in which case an applicator of the type shown in Figs. 2 and 11 preferably is used, while if it is desired to coat a plurality of rollers simultaneously to assure of maximum uniformity in the coating, an applicator of the type shown in Fig. 1 is employed.

Since the spindles 15 and 16 center the lower ends of the shafts or cores of the rollers while the upper ends thereof rest on the peripheries of the rolls 47 and 47a, the latter are adjustable vertically to effect the disposition of the rollers to be coated in parallelism with the line of travel of the applicator. A single roller may be coated by a machine equipped with a dual applicator as will be seen.

10 While the preferred embodiment of the invention has been shown and described, it will be apparent that various changes in details may be resorted to without departing from the spirit of the invention as defined by the appended claims.

15 We claim:

1. A machine for simultaneously coating a pair of printers' rollers comprising rotary means for supporting the rollers in parallel inclined position at different elevations and rotating the 20 rollers while in such position, coating applying means having a section for each of said rollers, an inclined guide for guiding said applying means longitudinally of said rollers from the upper to the lower ends of the coatable surfaces 25 thereof, means for so moving said applying means, means for supplying coating composition continuously to said sections of said applying means during the coating operation and means for maintaining the composition in said sections 30 at equivalent levels relatively to the respective rollers.

2. A machine for coating a pair of printers' rollers simultaneously comprising means for rotatably supporting said rollers in parallel relation but at different elevations, an inclined applicator provided with a discharge opening at the lower end and movable longitudinally beneath the rollers provided with walls partially enclosing the rollers for applying coating composition thereto, and means for supplying composition continuously to said applicator at the higher end thereof during the coating operation and in substantial excess of that required for coating the rollers whereby a current of said 35 composition flows continuously through the applicator from the upper to the lower end thereof and through said discharge opening during the coating operation.

3. A machine for coating a plurality of printers' rollers simultaneously comprising rotatable means for supporting said rollers in parallel relation, an applicator movable longitudinally of the rollers during rotation thereof for applying coating composition to the rollers, means comprising an intake for supplying coating composition to said applicator continuously during the coating operation, and means for supporting said applicator in an inclined position for facilitating the flow of the composition from the intake 50 transversely of the applicator for effecting the uniform coating of said rollers.

4. A machine for coating printers' rollers comprising an inclined guide provided with means for rotatably supporting the upper end or ends 55 of one or more printers' rollers, rotatable drive means adjacent the lower end of the guide for supporting the lower end or ends of said roller or rollers and rotating the same, a carriage movable longitudinally of said guide throughout the 60 length of the coatable surface of said roller or rollers and parallel with the latter and comprising a composition applicator receptacle, means for supplying coating composition to said receptacle for application thereby to said roller or rollers during movement of the same longi- 65

tudinally of said guide, a flexible driven chain releasably attachable to said carriage for moving the latter and said receptacle longitudinally of said roller or rollers during the coating operation, a rotary sprocket carried by said carriage and meshing with said chain, and means for latching the sprocket against rotation for causing the chain to move said carriage along said guide.

5. A machine for coating printers' rollers comprising rotary members for supporting the ends of one or more rollers in parallel and inclined position, means for rotating said rollers, a composition applicator beneath said rollers and partially enclosing the same for applying coating material thereto, means for supplying composition material to the applicator, means for moving said applicator lengthwise of the rollers from the upper to the lower ends of the coatable surfaces thereof during the rotation of the same, and tensioning means resisting said movement of the applicator for inhibiting the development of chattering action therein during the coating operation.

6. A machine for coating printers' rollers comprising an inclined guide, upper and lower rotary members for supporting the respective core ends of a pair of parallel rollers to be coated, means for rotating certain of said rotary members for rotating the rollers supported thereby, a movable carriage on said guide comprising a composition applicator for applying composition to said rollers, an endless chain provided with one run thereof supported for movement in a direction parallel with the movement of said carriage, a latchable pinion for effecting a driving engagement of said carriage with a link of said run for moving said carriage downwardly along said guide during the coating operation and means acting against the downward movement of said carriage for retaining said pinion against relative movement with respect to an engaged link of the chain.

7. A machine for coating printers' rollers comprising an inclined guide, upper and lower rotary members for supporting the respective core ends of a pair of parallel rollers to be coated, means for rotating certain of said members for rotating the rollers supported thereby, a movable carriage on said guide comprising a composition applicator for applying composition to said rollers, an endless flexible driving member having a run thereof disposed parallel with the direction of movement of said carriage, latchable rotary means on said carriage for effecting a driving engagement of said flexible member with said carriage for moving the same and said applicator along said guide during the coating operation, and means for unlatching said rotary means for releasing said carriage from engagement with said flexible member at the end of the coating operation.

8. A machine for coating printers' rollers comprising an inclined guide, upper and lower rotary members for supporting the respective core ends of a roller or rollers to be coated, means for rotating said roller or rollers during the coating operation, a movable carriage supported by said guide provided with a composition applicator movable along the roller or rollers, driving means for said carriage comprising an endless chain having one run thereof disposed parallel with the direction of movement of said carriage, means for effecting a driving engagement of said carriage with said run comprising a latch- 75

able sprocket on said carriage disposed in meshing relation with the links of said chain, and means for latching said sprocket against rotation to effect movement of the carriage and applicator along said guide during the coating operation.

9. A machine for coating printers' rollers comprising an inclined guide, upper and lower rotary members for supporting the respective core ends of a roller or rollers to be coated, means for rotating said roller or rollers during the coating operation, a movable carriage supported by said guide provided with a composition applicator movable along the roller or rollers, driving means for said carriage comprising an endless chain having one run thereof disposed parallel with the direction of movement of said carriage, means for effecting a driving engagement of said carriage with said run comprising a latchable sprocket on said carriage disposed in meshing relation with the links of said chain, means for latching said sprocket against rotation to effect movement of the carriage and applicator along said guide during the coating operation, and means adjacent the lower end of said guide for effecting the automatic release of said sprocket and interrupting the downward movement of the carriage.

10. A machine for coating a pair of printers' rollers simultaneously comprising an applicator having communicating coat applying sections for the rollers to be coated, means for supporting the rollers in parallel relation, means for rotating said rollers, means for moving the applicator longitudinally of the rollers during the coating operation, a composition inlet in one of said sections for supplying composition to both sections, a composition outlet in the other section, and adjustable means for maintaining the

composition at predetermined levels in each of said sections.

11. A machine for coating a pair of printers' rollers simultaneously comprising an applicator having communicating coat applying sections for the rollers to be coated, means for supporting the rollers in parallel relation, means for rotating said rollers, means for moving the applicator longitudinally of the rollers during the coating operation, a composition inlet in one of said sections for supplying composition to both sections, a composition outlet in the other section, and independently adjustable flow control members one between said sections and the other at said outlet for maintaining the composition at a predetermined level in each section.

12. A machine for coating a pair of printers' rollers simultaneously comprising means for rotatably supporting said rollers in parallel relation but at different elevations, an inclined applicator provided with a discharge opening at the lower end and movable longitudinally beneath the rollers and provided with walls partially enclosing the rollers for applying coating composition thereto, means for supplying coating composition continuously to said applicator at the higher end thereof during the coating operation and in substantial excess of that required for coating the rollers whereby a current of composition flows continuously through the applicator from the upper to the lower end thereof and through said discharge opening during the coating operation, and adjustable means for regulating the flow of composition material through said discharge opening for controlling the level of material in said applicator.
